UNITED STATES PATENT OFFICE.

HERMAN LEINEWEBER, OF CHICAGO, ILLINOIS, ASSIGNOR TO L AND L PNEUMATIC TOOL COMPANY, A CORPORATION OF ILLINOIS.

ROCK-DRILL.

SPECIFICATION forming part of Letters Patent No. 691,556, dated January 21, 1902.

Application filed May 27, 1901. Serial No. 62,120. (No model.)

To all whom it may concern:

Be it known that I, HERMAN LEINEWEBER, a citizen of the United States, residing at Chicago, in the county of Cook and State of Illinois, have invented a new and useful Rock-Drill, of which the following is a specification:

My invention relates to improvements in fluid-actuated drills generally, and more especially in pneumatic rock-drills.

10 My object is to provide a drilling implement of a comparatively simple and generally improved construction for use more especially in mining and wherein the motive fluid besides operating the drill-hammer also furnishes power to turn and feed the drill.

In the drawings, in which my invention is applied to a pneumatic rock-drill for use in mines, Figure 1 is a broken side elevation of the device mounted upon a support, which is shown in section; Fig. 2, an enlarged broken and longitudinal section of the rear end portion of the device, showing a rotary engine or motor for turning the drill; Fig. 3, an enlarged broken and longitudinal section of the device at its support on line 3 in Fig. 4; Fig. 4, a broken section taken on line 4 in Figs. 1 and 3; Fig. 5, an enlarged broken and longitudinal section of the forward or pneumatic-hammer portion of the device; Fig. 6, a section taken on line 6 in Figs. 1 and 5; Fig. 7, an enlarged perspective view of a slide-valve forming part of the construction of the pneumatic hammer; Fig. 8, a sectional rear end view of the device, the section being taken on line 8 in Fig. 2; Fig. 9, a section on line 9 in Figs. 1, 2, and 10; Fig. 10, a section taken on the irregular line 10 in Fig. 8; Fig. 11, a section taken on line 11 in Figs. 1, 2, and 10; and Fig. 12, a view the same as Fig. 11, 40 but with parts removed and other parts shown in broken section.

A is a tubular casing containing the pneumatic-hammer mechanism and provided in its forward end with a drill-receiving chuck a. The casing A is upon the end of a shaft B and is, in effect, a part thereof. The shaft carries a bushing b, which fits in the end portion of the casing, the bushing being fastened to the shaft by means of a cross-pin b', as shown in Fig. 5. A pin b'' passes through the casing, bushing, and shaft to fasten them se-

curely together. Loosely surrounding the shaft B is a threaded sleeve or feed-screw B', fitting at one end loosely into an annular socket b'' in the rear end of the casing A and provided at its rear end with a clutch member B'' in the form of a ratchet-wheel. (See Fig. 11.) On the shaft B is a disk C, fastened rigidly to the shaft by means of set-screws c, Fig. 12. The disk C has an annular flange 60 C' extending over the ratchet B'', and integral with the disk and extending inward from the flange at diametrically opposite sides are cored bosses C'', presenting radial guide-openings c'.

C, C'' are ratchet-engaging plungers or dogs having heads d, formed with ratchet-engaging teeth or projections d', the heads being upon the ends of shanks or stems d'', movable in the guide-openings c'. Extending transversely across the openings c' are pins c'', and confined between the pins c'' and heads d are springs d'', which tend normally to press the dogs C'' into engagement with the ratchet B''. The operation of the dogs and ratchet is like that of a friction-clutch, and, in effect, they constitute a friction-clutch as the parts turn in the direction of the arrows in Fig. 11.

D is the casing of a rotary pneumatic engine or motor formed with central bearings 80 e e', Fig. 2, for the rear end of the shaft B. In the casing D is a chamber D', closed at its forward side by a disk or cylinder head D''. Extending longitudinally and centrally through the shaft B is an opening or passage 85 B'', which reaches from the rear end nearly to the forward end of the shaft, where it turns outward through the side of the shaft and bushing b to produce the opening B''. On the rear wall or end of the casing D is a boss 90 D'', and extending into one side thereof is a cored passage f, leading to cored passages f' f''. Interposed in the passages f' f'' are valves g g', respectively, working through stuffing-boxes g'' g'', respectively, and having handles 95 g'' g'', respectively. The passage f' leads to and registers with the end of the passage B'' in the shaft B. The passage f'' leads to branch passages f'' f'', Fig. 10. Coupled to the boss D'' at the opening or passage f is a compressed-air-supplying hose Y. The circumferential wall of the chamber D' forms

an annular bearing-surface h , and the bearing e' is in a hub or central boss h' , integral with the casing D and projecting about halfway across the chamber D'. In the said 5 chamber is a solid wheel or disk E, fitting into and conforming in shape to the interior of the chamber. The wheel E is fastened, by means of a key i or otherwise, to the shaft B. Formed in the circumferential face of the 10 wheel is an annular groove k , and equidistant from each other in the wheel are radial recesses k' , in which are placed radially-sliding blades or wings k^2 of angular shape, as best shown in Fig. 2. These radially-sliding 15 blades are of a width corresponding to the width of the annular groove k , and their inner ends are reduced, as shown. The casing D is formed at diametrically opposite sides with 20 projections or ears D⁴, Fig. 8, with openings between them through the circumferential wall of the casing. Fitting into these openings are cam-blocks F F', fastened in place by means of pins l . On the inner faces of the blocks F F' are inwardly-projecting parts l' , which 25 extend into and conform in cross-section to the groove k of the wheel E, and they present along opposite end portions longitudinally-extending cam-surfaces $l^2 l^3$. The central boss h' is cut away opposite the cams $l^2 l^3$, as shown 30 in Fig. 9, to present recesses h^2 , the base-lines of which conform to and are parallel with the lines of the cams $l^2 l^3$. Extending through the blocks F F' at their cam-surfaces l^2 are air-inlet ports m , and extending through the 35 blocks at their cam-surfaces l^3 are exhaust-ports n . The ports m communicate with the air-supply passages $f^3 f^4$, and the ports n lead to the outside air. The projections l' form stationary abutments in the groove or recess 40 k , and the cams $l^2 l^3$ and wall h form the outer guide-surface along which the wings k^2 move and against which they are held by centrifugal force to slide. Air entering through the ports m to the groove k in the wheel bears 45 against the wings k^2 and forces the wheel and shaft B around. When the wings reach the cam-surface l^2 and surfaces h^2 , they are guided radially inward, permitting the air to escape through the outlet-ports n . As the 50 wings pass the abutments they slide outward along the cam-surfaces l^3 , past the inlet-ports m , and are propelled forward by the air entering at said inlets. The cam-blocks F are removable to give access to the interior of the 55 motor-chamber, and they may be replaced by new blocks at little expense in the event that their cam-surfaces become worn. The wheel E and shaft B are rotated continuously while the air-pressure is on, and this air-pressure 60 may be regulated or entirely shut off by turning the valve g' .

In the casing A is pneumatic-hammer mechanism of a construction similar in the main to that shown in Letters Patent of the United States No. 662,675, granted November 27, 1900, to George Leininger and myself jointly. The casing A contains a cylindrical cham-

ber divided by a partition p into two compartments $p' p^2$. In the compartment p' is a piston q , and in the compartment p^2 is a combined piston and hammer-head q' . The pistons are connected by a stem q^2 , passing through a guide-opening in the center of the partition. Also in the partition is a guide-opening in which works a slide-valve r . In 70 the ends of the valve r are recesses $r' r^2$, respectively, and in the opposite side of the valve are longitudinally-extending grooves $r^3 r^4$. Cored in the shell A is an air-supply passage s , communicating with the end B⁴ of 80 the passage B³ and provided in its opposite end with closely-adjacent ports $s' s^2$, which pass through the edge of the partition p to the guide-opening in which the slide-valve r works. Extending from the outside of the 85 casing through the partition p to the said guide-opening is a vent-passage t , registering with the groove r^4 of the slide-valve. Also passing through the partition from the outer side of the shell to the said guide-opening is a 90 spring-pressed pin t' , which engages the groove r^3 in the slide-valve to prevent the latter's turning. Air to operate the pneumatic hammer enters through the passages f, f', B^3 , and s and is controlled by the valve g . In the shell 95 A are the exhaust-ports v, v', v^2 , and v^3 , located as shown. When the parts are in the position shown in Fig. 5, the slide-valve r closes the port s' and opens the port s^2 , whereby the air enters to the compartment p^2 , against the piston q' , and forces said piston or hammer forward. As the said piston nears the end of its stroke the piston q engages the valve r and slides it until it closes the port s^2 and opens the port s' . The action of the pistons 100 is then reversed. While the pistons are being forced in the forward direction, air is vented from the compartment p^2 through the ports v^3 , while air is vented from the compartment p' through the groove r^4 in the valve 105 and port t . In the reverse movement of the pistons air from the compartment p^2 is vented through the groove r^4 and passage t , and the air in the compartment p' in front of the piston is vented through the port v . When the 110 piston is forced forward to the end of its stroke, the compressed air behind the piston q' vents through the opening v^2 , while at the end of the return stroke the compressed air 115 behind the piston q vents through the port v' . In the chuck a is a drill X, against which the hammer strikes.

Any suitable support for the drill device may be provided. In the construction illustrated in Fig. 1 the support comprises a pair 120 of standards G, one only being shown, the standards being provided at their lower ends with jacks G', whereby they may be tightened in place. Adjustable up and down upon the standards is a shaft or cross-bar G². 125

H is a bearing block or collar, and formed integral therewith is a split collar H', which may surround the shaft G² and be fastened thereto in any adjusted position by means of

the tightening-screw H^2 . The collar H may be turned to any angle or position upon the shaft G^2 and tightened when adjusted. Resting upon the collar H is a supporting-head I , provided with a downwardly-extending shaft I' , passing through the bearing-collar H . On the vertical shaft I' , at the under side of the collar H , is a bracket-arm K , held in place upon the shaft I' by nuts I^2 . The bracket-arm K has a smooth upper face, with guide-flanges K' at opposite sides. The casing D is formed at its under side with an angular or dovetail socket D^5 to fit over the guide-flanges K' and slide thereon. Extending through the head I is a smooth opening I^3 for the feed-screw B' to pass through. In opposite sides of the head I are slots I^4 to receive laterally-sliding sectional nuts I^5 to engage the feed-screw. Passing transversely through the head I is a shaft I^6 , provided toward opposite ends, respectively, with right and left hand screw-threads to engage threaded openings in the said sectional nuts. Midway between ends the shaft I^6 has an annular recess I^7 , into which projects the end of a pin I^8 , whereby the shaft may be rotated, but is held against longitudinal movement. The sectional nuts I^5 are shaped to engage and release the feed-screw B' . On the shaft I^6 is a handle I^9 , which when turned to the stop I^{10} in Fig. 1 moves the sectional nuts into engagement with the feed-screw B' and when turned to the stop I^{11} moves the dogs out of engagement with the said feed-screw.

35. In operation—in a tunnel, for example—the device may be placed in position by causing the standards G to stand in the vertical plane when they are fastened in place by means of the jacks G' . The sleeve H' , carrying the working parts, may be slid laterally to any position upon the bar G^2 and turned to any angle desired and fastened, as aforesaid, in adjusted position by means of the screw H^2 . The shaft I' , passing through the collar H , forms a swivel connection whereby the drill and bracket K may be turned to any desired angle. The valve g may be opened far enough to admit the desired amount of pressure to the hammer to cause the same to work with the speed and force desired. The valve g' may be opened far enough to admit the necessary amount of pressure to cause the rotary motor to turn the shaft B with the speed and power desired. The operator will be able to judge of the power and speed he is getting during the operation and manipulate the valves g g' accordingly. The hammer device may be operated to produce impacts against the end of the drill X with great speed and force, and it will be a simple matter to regulate the turning of the drill in accordance with the character of the rock being operated upon. To feed the drill forward, the operator turns the handle I^9 to the stop I^{11} , causing the sectional nut I^5 to engage the feed-screw B' . As before explained, the feed-screw B' is held to the shaft by the engagement of the spring-

dogs C^3 with the ratchet B^2 . When the resistance to the feed is greater than desired, the dogs will wipe over the ratchet-teeth. The springs d^3 on the dogs are sufficiently stiff to cause the dogs to engage with desired force the slanting sides of the ratchet-teeth and form frictionally-held feeding means, and they will slide over the teeth whenever the resistance to the feed is greater than desired. By leaving the sectional nut I^5 in engagement with the feed-screw the feed of the drill will be properly maintained by the clutch mechanism C^3 B^2 , and no accident to the mechanism can happen by reason of overcrowding the feed. It will be understood that as the drill is fed forward the casing D moves forward upon the guide-flanges K' of the bracket-arm K . When the hole has been made by the drill, the handle I^9 may be turned back to the stop I^{10} to release the sectional nut I^5 from the feed-screw, when the parts may be readily slid on the bracket K to the initial position, (shown in Fig. 1,) withdrawing the drill from the hole.

Whenever it is desired to use the device as an auger alone, as in drilling through soft-rock or material, the hammer may be shut off and the turning and feeding mechanisms alone actuated. When desired, the rotary motor may be thrown out of operation while the hammer is in operation.

While I prefer to construct my improvements throughout as shown and described, they may be variously modified in the matter of details without departing from the spirit of my invention as defined by the claims.

What I claim as new, and desire to secure by Letters Patent, is—

1. In a rock-drill, the combination with a drill-holder of a fluid-pressure-actuated hammering device on the drill-holder, and a fluid-pressure-actuated rotary motor on the drill-holder operating to turn and advance it.

2. In a rock-drill, the combination of a drill-holding shaft, a fluid-pressure-actuated drill-hammering device on the shaft, a fluid-pressure-actuated rotary motor on the shaft operating to turn it, a feed-screw upon the shaft, and relatively stationary feed-screw-engaging means for advancing the rotary shaft.

3. In a rock-drill, the combination of a drill-holding shaft, a fluid-pressure-actuated drill-hammering device on the shaft, a fluid-pressure-actuated rotary motor on the shaft operating to turn it, a feed-screw upon the shaft, a friction-clutch between the feed-screw and shaft, and relatively stationary feed-screw-engaging means for advancing the rotating feed-screw and shaft.

4. In a rock-drill, the combination of a shaft, a drill-holding casing on the forward end of the shaft, fluid-pressure-actuated drill-hammering mechanism in said casing, a fluid-pressure-actuated shaft-turning rotary motor on the rear end portion of the shaft, and shaft-advancing feed-screw mechanism between the said casing and motor.

- 4
5. In a rock-drill, the combination of a shaft, a drill-holding casing on the forward end of the shaft, fluid-pressure-actuated drill-hammering mechanism in said casing, a fluid-pressure-actuated shaft-turning rotary motor on the rear end portion of the shaft, shaft-advancing feed-screw mechanism between the said casing and motor, and a fluid-pressure-supply passage extending longitudinally 10 through the shaft to said casing.
6. In a rock-drill, the combination with a support of a drill-holding shaft, a fluid-pressure-actuated drill-hammering device on the forward end of the shaft, a casing on the opposite end portion of the shaft slidably mounted on said support, a fluid-pressure-actuated shaft-turning rotary motor in said casing, and shaft engaging and releasing feed mechanism for advancing the rotating shaft.
- 15 7. In a rock-drill, the combination with a drill-holding shaft of a shaft-turning rotary motor comprising a peripherally-grooved wheel fixed to the shaft, a relatively stationary chamber having a cylindrical bearing-wall 75 about the wheel, removable and replaceable cam-blocks interposed in said wall and extending into the groove of said wheel, motive-fluid inlet and outlet ports in the cam-blocks and radially-sliding wings in said wheel movable in sliding contact with said bearing-wall and cam-blocks, substantially as described.
- 20 8. In a drilling device, the combination of a drill-holder, fluid-pressure-actuated drill-hammering mechanism thereon, separate fluid-pressure-actuated rotating mechanism for the drill-holder, and means for throwing the hammering mechanism into and out of action, whereby the drill may be operated by the rotating mechanism alone, substantially 25 as described.
- 35 9. In a drilling device, the combination of a drill-holder, fluid-pressure-actuated drill-hammering mechanism thereon, separate fluid-pressure-actuated rotating and feeding mechanism for the drill-holder, and means for throwing the hammering mechanism into and out of action, whereby the drill may be operated by the rotating and feeding mechanism alone, substantially as described.
- 40 10. In a drilling device, the combination of a drill-holder, fluid-pressure-actuated drill-hammering mechanism thereon, separate fluid-pressure-actuated rotating mechanism for the drill-holder, fluid-pressure-actuated feeding means for the drill-holder, and separate fluid-pressure-controlling means for the
- hammering and rotating mechanisms whereby they may be caused to operate together, or either may be thrown out of operation independently of the other.
11. In a drilling device, the combination of a drill-holder, fluid-pressure-actuated drill-hammering mechanism thereon, separate fluid-pressure-actuated rotating mechanism for the drill-holder, fluid-pressure-actuated feeding means for the drill-holder, and separate controlling means for the hammering, rotating and feeding mechanisms, whereby either may be thrown out of operation, substantially as and for the purpose set forth.
- 15 12. In a rock-drill, the combination with a drill-holding shaft of a shaft-turning rotary motor comprising a peripherally-grooved wheel fixed to the shaft, a relatively stationary chamber having a cylindrical bearing-wall 75 about the wheel, removable and replaceable cam-blocks interposed in said wall and extending into the groove of said wheel, motive-fluid inlet and outlet ports in the cam-blocks and radially-sliding wings in said wheel movable in sliding contact with said bearing-wall and cam-blocks, substantially as described.
13. In a rock-drill, the combination with a support of a drill-holding shaft, a fluid-pressure-actuated drill-hammering device on the forward end of the shaft, a casing on the opposite end portion of the shaft slidably mounted on said support, a fluid-pressure-actuated shaft-turning rotary motor in said casing, a feed-screw upon the shaft, a friction-clutch between said shaft and feed-screw, and feed-screw-engaging means on the support for advancing the rotating feed-screw and shaft.
- 18 14. In a rock-drill, the combination with a support of a drill-holding shaft, a fluid-pressure-actuated drill-hammering device on the forward end of the shaft, a casing on the opposite end portion of the shaft slidably mounted on said support, a fluid-pressure-actuated shaft-turning rotary motor in said casing, a feed-screw upon the shaft, a friction-clutch between said shaft and feed-screw, and an adjustable feed-screw engaging and releasing sectional nut on the support for advancing the rotating feed-screw and shaft, substantially as described.

HERMAN LEINEWEBER.

In presence of—

ALBERT D. BACCI,
D. W. LEE.
